United States Patent Office

Des. 233,395
Patented Oct. 29, 1974

233,395

FURNITURE PANEL OR THE LIKE

Huey T. Keller, High Point, N.C., assignor to Empire
Furniture Corporation, Johnson City, Tenn.

Filed Sept. 9, 1971, Ser. No. 179,263

Term of patent 14 years

Int. Cl. D6—06

U.S. Cl. D6—192

fig. 4

fig. 3

fig. 2

fig. 1

fig. 6

fig. 5

6

FIG. 1 is a front elevational view of the furniture panel or the like showing my new design; the verso thereof being substantially flat and unornamental;

FIG. 2 is a section taken through lines 2—2 of FIG. 1;

FIG. 3 is a front elevational view of a modification of the furniture panel or the like, the verso thereof being substantially flat and unornamental;

FIG. 4 is a section taken through lines 4—4 of FIG. 3;

FIG. 5 is an even further modification of the furniture panel or the like showing my new design, the verso thereof being substantially flat and unornamental; and

FIG. 6 is a section taken through lines 5—5 of FIG. 5.

I claim:

The ornamental design for a furniture panel or the like, as shown.
